UNITED STATES PATENT OFFICE.

ELMER H. OVERSMITH, OF BUFFALO, NEW YORK, ASSIGNOR TO BUFFALO TRUCK & TRACTOR CORPORATION, OF BUFFALO, NEW YORK, A CORPORATION OF NEW YORK.

DESIGN FOR A RADIATOR.

55,312.

Specification for Design.

Patented May 25, 1920.

Application filed October 17, 1919. Serial No. 331,488. Term of patent 14 years.

To all whom it may concern:

Be it known that I, ELMER H. OVERSMITH, a citizen of the United States, residing at Buffalo, in the county of Erie and State of New York, have invented a new, original, and ornamental Design for Radiators, of which the following is a specification, reference being had to the accompanying drawing, forming part thereof.

Figure 1 is a side elevation of a radiator showing my new design. Fig. 2 is a top plan view of the same.

I claim:

The ornamental design for a radiator, as shown.

ELMER H. OVERSMITH.
